UNITED STATES PATENT OFFICE.

EDWARD NEWELL CASE, OF SAN DIEGO, CALIFORNIA.

FUEL-REGULATING MEANS FOR EXPLOSION-ENGINES.

1,300,344.

Specification of Letters Patent. Patented Apr. 15, 1919.

Application filed February 26, 1918. Serial No. 219,333.

To all whom it may concern:

Be it known that I, EDWARD NEWELL CASE, a citizen of the United States, and a resident of San Diego, in the county of San Diego and State of California, have invented certain new and useful Improvements in Fuel-Regulating Means for Explosion-Engines; and I do hereby declare that the following is a full, clear, and exact description thereof, reference being had to the accompanying drawings, and to the characters of reference marked thereon, which form a part of this specification.

This invention relates to automatic means for supplying to an explosion engine an explosive mixture, such as a mixture of a hydrocarbon and oxygen, in such manner as to maintain the constituents of the mixture properly proportioned, regardless of the altitude of the engine and the consequent barometric operative pressure.

The invention is herein shown and is more specifically applicable to the engines of flying machines, wherein the operative barometric pressure of the engine is subject to wide variations.

The purpose of the invention is to provide means for regulating the pressure of air delivered to the carburetor or mixing device of the engine, together with a proper proportion of the hydrocarbon constituent of the explosive mixture, so designed and arranged as to maintain the proportions of the oxygen and the hydrocarbon constituents of the mixture uniform regardless of the altitude of the engine.

In supplying the explosive mixture to a gasoline or like explosion engine the proper proportions of oxygen and carbon to produce a mixture of the desired proportions can be determined and maintained for any given altitude or barometric pressure, but when the engine changes its altitude, as when a flying machine engine ascends from a lower to a higher altitude, the barometric pressure changes from normal at a known rate per foot of altitude, or vice versa, and inasmuch as the oxygen content of the atmosphere is dependent upon the pressure, the quantity of the oxygen per unit volume of air decreases as the engine rises from the earth and increases as it descends to the earth, if no means be provided for varying

the percentage of oxygen relatively to the volume of air.

Heretofore it has been a common practice to equip a flying machine with means for carrying oxygen under pressure, the oxygen being controllably releasable to the carburetor or fuel mixing device so that, as the machine rises to a higher altitude, the aviator may enrich the explosive mixture by injecting oxygen thereinto to correspond with the altitude determined by the scale of an altitude meter. If the proportion of the oxygen to the hydrocarbon constituent of the mixture be not maintained the power output of the engine will be decreased. Thereby the power of the engine to propel the machine is not only decreased, by reason of the rich explosive mixture, but is further decreased by reason of the decreased resistance of the rarer atmosphere against the propeller blades, so that the power of the machine is greatly reduced. If means be provided to maintain the substantially constant pressure of the air delivered to the carburetor or mixing device by which the oxygen of the air is mixed with the hydrocarbon constituent of the fuel, the proportion of the oxygen content of the air to the hydrocarbon constituent will be maintained at a ratio determined by a known barometric pressure, as, for instance, atmospheric pressure at the surface of the earth.

It is the purpose of the present invention to provide pressure regulating means automatically controlled by the barometric air pressure or other altitudinal atmospheric conditions to maintain the supply of air to the carburetor or mixing device at a substantially constant pressure, regardless of the altitude of the engine, so as to thereby maintain a proper ratio of the oxygen content of the air to the hydrocarbon constituent, which latter may be maintained constant or at any variable ratio, depending upon the hydrocarbon feed control.

A further object of the invention is to provide a novel mechanism for so maintaining the air pressure constant for the purpose set forth, which is connected to and driven by the engine.

A further object of the invention is to provide air pressure regulating means for the purpose set forth that is constructed

with means to render the regulating mechanism inoperative at a predetermined barometric pressure or other equivalent atmospheric condition.

- 5 Other objects of the invention are to improve, simplify, and increase the efficiency of means to supply explosive mixtures to a hydrocarbon explosion engine, and the invention consists in the combination and arrangement of the parts as shown in the drawings and described in the specification, and is pointed out in the appended claims.

In the drawings,

- 10 Figure 1 is an elevation, partially broken away, of a hydrocarbon explosion engine equipped with an explosive mixture regulating mechanism embodying my invention.

15 Fig. 2 is a section on the line 2—2 of Fig. 1, looking in the direction indicated by the arrows.

20 Fig. 3 is a fragmentary plan view of the mechanism partially broken away.

- 25 Fig. 4 is a fragmentary detail of the pressure pump driving mechanism hereinafter described.

30 In the illustrated embodiment of the invention, the element which is responsive to varying barometric pressures to control the pressure of air delivered to the carburetor or mixing device of the engine embraces a dia-
phragm which is acted upon at its opposite
35 sides by differentiated air pressures con-
trolled by a spring if desired, and the means
for creating and maintaining the pressure is
a pump, herein shown as a centrifugal mul-
tistage pump that is connected to and driven
40 by the engine through a speed change
mechanism that is itself under the control of
the pressure actuated element. It will be un-
derstood, however, that the mechanism may
45 assume other specific forms and that the ele-
ment which is responsive to barometric pres-
sures may be otherwise selected, as, for in-
stance, an aneroid barometer suitably con-
50 nected to the speed change mechanism for the
pump or other pressure device may be em-
ployed.

- 55 As shown in the drawings, 10 designates
as a whole the hydrocarbon explosion en-
gine, indicated as a four cylinder engine.
11, 11 designate carburetors or mixing de-
vices suitably connected to the intake valves
of the engine. 12 designates a manifold
connected to said carburetors. 14, 14 design-
60 nate hydrocarbon intakes leading to the
manifold. 15 designates an air intake lead-
ing also to said manifold. Said air intake
15 is designed to receive air directly from
the surrounding atmosphere through a pipe
65 16 connected to the intake through an or-
ifice controlled by a downwardly closing
check valve 17, or to receive air under pres-
sure through a pipe 18 which is connected to
a suitable pressure device, herein shown as
65 having the form of a two stage centrifugal

pump 19. 20 designates a supporting frame
for the propeller blades (not shown) which
is connected to and driven by the power shaft
21 of the engine. The pump 19 is shown as
located at the rear side of the engine, rela-
70 tively to the propeller support, and is driven
by any suitable form of speed change mech-
anism which is under the control of an ele-
ment responsive to barometric pressure.

75 The speed change mechanism herein shown
embraces two pairs of pulleys 22, 22 and
23, 23; that is to say, the pulleys 22 of
one pair are mounted on the engine shaft 21
and the pulleys 23 of the other pair being
80 mounted on the driving shaft 24 of the
pump 19. The said pairs of pulleys are cone
pulleys, with the bevel or cone faces of the
pulleys of each pair facing each other. The
pulleys 22 constitute the driving pulleys and
85 the pulleys 23 constitute the driven pulleys.
They are connected by a relatively thick belt
25 having beveled edges, as shown in Fig. 4,
to engage the cone faces of the pulleys. The
said pulleys of each pair are slidable on
their respective shafts and are so intercon-
nected that when the pulleys of one pair are
90 moved away from the other the pulleys of
the other pair are moved correspondingly to-
ward each other, and vice versa. With this
construction and arrangement it will be ob-
served that when the pulleys of one pair are
95 spaced from each other at a distance equal
to the spacing of the other pulleys on the
respective shafts, power delivered from the
driving or engine shaft will rotate the pump
100 or driven shaft at the same speed as the en-
gine shaft. When the pulleys on the engine
or driving shaft are spaced closer together
than those of the pump or driven shaft, and
the belt is, therefore, engaged with the cone
105 faces of the pulleys 22 near their periphery,
said pump shaft will be driven at a rate of
speed higher than the engine or driving
shaft. Conversely, when the pulleys on the
pump or driven shaft are spaced a distance
110 apart less than those on the engine or driv-
ing shaft said pump will be driven at a rate
of speed less than that of the engine or driv-
ing shaft.

115 The means herein shown for shifting the pulleys toward and from each other are made as follows:

120 The pairs of pulleys 22 and 23 are pro-
vided with grooved hubs 26, 27, respectively,
and the grooved hubs of corresponding pul-
leys of the respective pairs at each side of
the change feed mechanism are connected by
125 rock arms 28. Said rock arms have forms
29 that are provided with inturned studs 30
to travel in the grooved hubs 26. Said rock
arms are centrally provided with apertures
130 to receive the lower ends of rock shafts 31
which are rotatably mounted in sleeve 32,
herein shown as formed integral with a cas-
ing 33 which incloses the principal parts of

- the speed change mechanism. Said casing is equipped with suitable bearings for the engine and pump shaft. Said shafts are non-rotatively locked to the rock arms in any suitable manner. The rock shafts 31 are provided at their upper ends with eccentric or crank studs 34, there being two of such crank studs, one at each side of the change speed mechanism, as shown in Fig. 3.
- 10 35 designates a link that is provided at one end with a transversely slotted head 36 through which the crank or eccentric studs of the rock shafts extend, and in which they have bearing. The end of the link 35 remote from the slotted cross head 36 is connected to a diaphragm 37 which constitutes one wall of a casing 39, that is attached in any suitable manner, as by means of a clip 40 to the speed change mechanism casing 33.
- 15 20 The diaphragm is subjected at its outer side to the pressure of the surrounding air. The casing 39 is sealed and is filled with air at normal pressure at the earth's surface, to which pressure the inner side of the dia-
- 25 phragm 37 is subjected. The pressure exerted against the inner side of the diaphragm is, therefore, constant, while the pressure against the outer side of the dia-
- 30 phragm varies with the altitude of the machine.
- The construction and arrangement of the change speed mechanism and its co-operation with the pressure controlled element is such that when the machine is at the earth's sur-
- 35 40 face, or at any selected altitude, the pump driven mechanism is inoperative to drive the pump, and at such time air at normal pressure is admitted through the pipe 16 to the carbureting or mixing devices.
- 45 50 With the construction described it will be understood that constant air pressure action on the inner side of the diaphragm is counterbalanced by the normal atmospheric pressure at the level of the earth, as at a selected altitude, and under these conditions the pump driving mechanism is inoperative to drive the pump. When the machine rises in the air and pressure decreases on the outer side of the diaphragm, the constant pressure
- 55 60 on the inner side of the diaphragm tends to force the diaphragm outwardly away from the casing, and thus tends to shift the link 35 endwise to rock the shafts 31 in a direction which causes the cone pulleys 22 of the engine shaft to approach each other and the cone pulleys 23 of the pump shaft to recede from each other. Thus it will be seen that as the machine passes from one altitude to a higher altitude and the barometric pressure on the outside of the diaphragm decreases, the constant pressure on the inner side of the diaphragm serves to control the change speed device so as to operate the pump 19 at a velocity dependent upon the altitude the machine is traveling. Thus the

air pressure delivered by the pump may be maintained with respect to a predetermined pressure as, for instance, air pressure at the earth's surface. As the flying machine descends from a higher to a lower altitude the 70 barometric pressure acts counter to the constant pressure on the inner side of the dia-

75 phragm and tends to force the diaphragm inwardly and to act through the link 35, rock shaft 31 and rock arms 28 to spread 75 the pulleys apart and to shift the pulleys 23 together so as to decrease the speed of the pump and consequently to automatically decrease the pressure exerted by the pump to correspond to the barometric pressure in 80 which the flying machine is operating.

When the machine descends to the earth or into an altitude of a barometric pressure substantially the same as that at the surface of the earth, it is unnecessary to operate the 85 pump, and means are provided for automatically releasing the pump from its driving connections with the engine and to admit air to the fuel mixing device directly from the atmosphere at normal pressure. For this 90 purpose the engine shaft 21 is shown as provided between the cone pulleys 22 with a belt supporting disk or bearer 41 which is loosely mounted on the shaft and is so related to the cone faces of the pulleys 22 that when the 95 pulleys are separated sufficiently to release the belt therefrom the said belt rides upon the periphery of the freely rotative disk 41. In such adjustment no power is transmitted from the engine shaft to the pump shaft. 100 When the pump is thus stopped air is taken to the carbureters or mixing devices through the intake 16, the check valve 17 at this time opening upwardly to admit the air. The check valve is so located that when pressure 105 is developed in the pipe 18, said pressure closes the valve against its seat so that all of the air developed under pressure by the pump is admitted through the pipe 18. The air taken through the pump 19 is admitted 110 to the casing 33 by way of ports or openings 42 and thence to the central portion of the two stage or other type pump.

The specific embodiment of my invention has been described with considerable particularity as to detail, but it is to be understood that said description is not intended to be restrictive and that the invention is not limited thereto, except as to claims wherein said details are specifically set forth, or as 120 imposed by the prior art.

I claim as my invention:

1. Means for supplying an explosive mixture to a hydrocarbon explosion engine, comprising mechanism responsive to variations 125 of altitudinal atmospheric conditions to maintain constant the pressure of air delivered to the engine.

2. Means for supplying an explosive mixture of a hydrocarbon and air to an explo- 130

sion engine comprising a mixing device, constructed with means for delivering air and a hydrocarbon thereto, and means responsive to altitudinal variations of atmospheric conditions to regulate the pressure of air supplied to the mixing device.

3. Means for supplying an explosive mixture of hydrocarbon and air to explosion engines comprising a mixing device having 10 means for supplying hydrocarbon and air thereto, the air supplying means embracing a pressure device for supplying constant air pressures to the mixing device, and means responsive to altitudinal variations of atmospheric conditions for regulating the pressure device.

4. Means for supplying an explosive mixture of hydrocarbon and air to explosion engines comprising a mixing device having 20 means for supplying hydrocarbon and air thereto, the air supplying means embracing a pump, and means responsive to barometric conditions of the atmosphere to regulate the speed of the pump.

25 5. Means for supplying an explosive mixture of hydrocarbon and air to explosion engines comprising a mixing device having means for supplying hydrocarbon and air thereto, the air supplying means embracing a pump, means for driving the pump, including a speed change mechanism, and means responsive to barometric pressure for controlling the change speed mechanism.

6. The combination with an explosion engine, of means for supplying a mixture of hydrocarbon and air thereto, the air supplying means embracing a pressure device, with means for driving it from the engine, and means responsive to barometric pressures for controlling the speed of said pressure device.

7. The combination with an explosion engine, of means for supplying a mixture of hydrocarbon and air thereto, the air supplying means embracing a pressure device, a change speed mechanism connecting the engine to the pressure device for driving the latter, and means responsive to barometric pressures for controlling the speed change mechanism.

8. The combination with an explosion engine, of means for supplying a mixture of hydrocarbon and air thereto, the air supplying means embracing a pump, a change speed mechanism connecting the engine to the pump for driving the latter, embracing pairs of oppositely facing pulleys on the engine and pump shafts, with the pulleys of each pair movable toward and from each other, a belt between and engaging the cone faces of said pulleys, and means responsive to altitudinal variations of atmospheric conditions for controlling the movement of said pulleys toward and from each other.

65 9. The combination with an explosion en-

gine, of means for supplying a mixture of hydrocarbon and air thereto, the air supplying means embracing a pressure device, a change speed mechanism connecting the engine to the pressure device for driving the latter, embracing pairs of oppositely facing pulleys on the engine and pump shafts with the pulleys of each pair movable toward and from each other, rocking arms connected to the pulleys, and means responsive to barometric pressures to control said rocking arms.

10. The combination with an explosion engine, of means for supplying a mixture of hydrocarbon and air thereto, the air supplying means embracing a pressure device, a change speed mechanism connecting the engine to the pressure device for driving the latter embracing pairs of oppositely facing pulleys on the engine and pump shafts, with the pulleys of each pair movable toward and from each other, rocking arms connected to the pulleys, rock shafts attached to said rocking arms and provided with cranks, a slotted link connected to the cranks of said shafts, and means responsive to barometric pressure to shift said link endwise.

11. Means for supplying an explosive mixture of hydrocarbon and air to explosion engines, embracing means responsive to altitudinal variations of atmospheric conditions to regulate the pressure of air supplied to the mixture, constructed with means to automatically throw out the regulating means at a predetermined atmospheric condition.

12. Means for supplying a mixture of hydrocarbon and air to explosion engines comprising a mixing device having means to direct a hydrocarbon and air to the mixing device, and means responsive to barometric pressure for controlling the pressure of air delivered to the mixing device, said latter means being constructed with means to disconnect the pressure controlling means at a predetermined barometric pressure.

13. Means for supplying a mixture of hydrocarbon and air to explosion engines comprising a mixing device, with means for directing hydrocarbon and supplying air thereto, said air supply means embracing a pump, means to drive said pump, including speed change mechanism, and means responsive to barometric pressures for regulating the speed change mechanism, embracing means to disconnect the regulating means for the change speed mechanism at a predetermined barometric pressure.

14. The combination with an explosion engine and a fuel mixing device, of means for applying a hydrocarbon and air thereto, the air supplying means embracing a pump, means for driving the pump from the engine, embracing a speed change mechanism, comprising pairs of oppositely facing cone

pulleys of the pump and engine shafts, respectively, a belt connected between and engaging the cone faces of said pulleys, means responsive to barometric pressures for moving the pulleys of one pair toward each other simultaneously with the movement of the other pair away from each other, and a belt supporting carrier between the pulleys

of the engine shaft to support the belt when the pulleys are separated to disconnect the belt therefrom.

In testimony whereof I claim the foregoing as my invention, I hereunto append my signature at Chicago, Illinois, this 23rd day of February, 1918.

EDWARD NEWELL CASE.
